UNITED STATES PATENT OFFICE.

JOSEPH W. KENNA, OF CHICAGO, ILLINOIS, ASSIGNOR TO JAMES W. VAIL,
TRUSTEE, OF PORT WASHINGTON, WISCONSIN.

ТИЛТИНГ-ЧЕАР.

SPECIFICATION forming part of Letters Patent No. 374,971, dated December 20, 1887.

Application filed May 24, 1886. Serial No. 203,087. (No model.)

To all whom it may concern:

Be it known that I, JOSEPH W. KENNA, a citizen of the United States, residing at Chicago, county of Cook, State of Illinois, have 5 invented certain new and useful Improvements in Tilting-Chairs, of which I do declare the following to be a full, clear, and exact description, reference being had to the accompanying drawings, forming part of this specification.

10 My invention relates to tilting-chairs of that class wherein the chair-seat is separate from the tripod-like base, being mounted upon the arms of the spider-frame pivotally joined to an upright standard or support. The lower 15 portion of the standard constitutes a spindle, which is ordinarily screw-threaded, to engage with counter-threads in the perforated base-nut, said nut having the legs of the chair secured thereto. The chair-seat, spider-frame, 20 and spindle turn together about the tripod-base, and are adjustable as to height, usually by the screw action of the spindle with the base-nut. A coil-spring secured between the standard and the spider-frame controls the 25 tilting movement of the chair-seat and frame about the standard-pivot, and by adjustment in tension enables the chair to be adapted to the comfort of the occupant.

The invention is designed to produce a cheap, 30 simple, and efficient chair of the kind mentioned; and to that end it consists in certain improvements in the structure and organization of the parts located between the chair seat and base, such parts, in combination, being known 35 to the trade as the "irons."

The nature of said improvements will fully appear from the following description, and be distinctly pointed out in the claims at the conclusion thereof.

40 Figure 1 is a view in side elevation; Fig. 2, a view in longitudinal vertical section, and Fig. 3 a view in longitudinal horizontal section. Fig. 4 is a view in front elevation of one form of my invention employing double 45 springs. Figs. 5, 6, 7, and 8 are views similar to Figs. 1, 2, 3, and 4, respectively, showing the organization of the parts when a single spring is employed.

The base-nut A is of the usual construction, 50 being provided with the recesses or seats to

receive the ends of the legs of the chair, which extend thence, as well understood, in tripod-like fashion to furnish the base-supports. The threaded spindle B screws into the nut A in the usual manner, and carries at its upper end 55 the enlarged standard C, to which is pivoted, as at c, the dependent ears d of the spider-frame. The spider-frame is provided with the usual arms, e, which extend substantially in horizontal direction, and furnish supports at 60 their ends for the frame of the chair-seat, which is secured thereto.

Cast in one piece with the spider-frame and the ears d depending therefrom is an expanded head or plate, f, located between the ears and 65 furnished with screw-like lugs g, which afford bearings or seats for the ends of the coil-springs D. The standard C extends upward in direction substantially parallel to the expanded face f of the spider-frame, and contacts therewith, near its upper end, when the chair-seat is in horizontal position, to limit the movement thereof about the pivot c. When the chair is tilted backward, the rib r on the spider-frame glides into the seat s on the 70 standard C, and thus checks the movement of the chair about the pivot c at the same time that the frame and seat are held from sidewise play. The retention-rod G carries thereon a screw-like bearing-plate, g', against which the 75 end of the coiled springs D may abut, said springs being thus securely seated between the bearings g g', located upon the spider-frame, and the retention-rod, respectively. The spider-frame and the standard are perforated or 80 otherwise cut away, to permit the free passage of the retention-rod G, which, at its end opposite to the bearing-plate g', is screw-threaded to receive the hand-wheel H or like adjusting device. The pivot-plate h, sliding freely upon 85 said rod and bearing against seats upon the standard C, serves to sustain said rod in position against the tension of the spring D and to permit the radial shift of the rod without disarrangement of the parts or undue strain 90 during the tilting movement of the spider-frame about the pivot c.

The adjusting-wheel H turns freely at its end within a socket of the pivot-plate h, so that with such plate as a bearing the wheel H may 95

be rotated, and the rod G be in consequence drawn back or forth to vary the tension of the springs D. If desired, the position of the hand-wheel H upon the rod G may be reversed—that is, said wheel may rest against the bearing-plate g', instead of against the pivot-plate h, as shown, in which event the rod G would be also reversed end for end, so as to receive the wheel in the new relation and to retain the pivot-plate h.

In order that the spindle B and its standard may not be jammed tight down against the base-nut A, which sometimes wrenches the standard from the spindle, there is provided a lug, k, projecting from the standard, and as the downward rotation of the spindle proceeds engaging with the shoulder or terminal of a vanishing recess or seat (shown at 1, dotted lines, Fig. 8) in the top plate, K, of the base-nut. The stop k arrests the rotation of the spindle B before the standard can jam against the base-nut A, and in consequence saves such parts from strain and danger of breakage. Manifestly the like result would be attained by making a lug on the cap-plate K of the base-nut of sufficient height to contact with some projecting portion of the standard.

By pivoting the spider-frame to the standard C at the point c, near to the base, a firm, strong joint is secured at the same time that the leverage of the chair-seat in tilting is greatest. In consequence the movement against the tension of the spring D is even and comfortable, the retention-rod G shifting about, together with its radial pivot-plate h, so as to avoid undue strain at the same time that a substantially direct thrust upon the coil-springs D is maintained during the tilting movement. The spider-frame may be pivoted to the standard at some other point above the pivot c, although such position is deemed the most desirable in practice.

The general combination, in a tilting-chair iron, with the standard thereof, the spider pivoted thereto, a coil-spring, and an adjust-

ing-rod and hand-wheel, of a pivoted plate bearing against the standard and sustaining the adjusting-rod, is not claimed herein, the same being the subject of a separate application filed by me September 22, 1884, Serial 50 No. 143,638.

Having thus described my invention, what I claim as new, and desire to secure by Letters Patent, is—

1. The combination, with the upright standard, of the spider-frame mounted thereon and tilting about the same, and provided with a dependent face-plate to rest against the standard, the retention-rod pivotally sustained at one end upon said standard, extending freely through said standard and face-plate, and carrying at its opposite end an expanded bearing-plate, a compression-spring seated between and against said bearing and face plates, respectively, and a hand-wheel threaded to the retention-rod to vary the tension of said spring, substantially as described. 55

2. The combination, with the upright standard, of the spider-frame mounted thereon and tilting about the same, and provided with a dependent face-plate to rest against the standard, the retention-rod extending freely through said standard and face-plate, and carrying near one end a stay-plate set pivotally against said standard, and at its opposite end an expanded bearing-plate, a compression-spring seated between and against said bearing and face plates, respectively, and a hand-wheel threaded to the retention-rod and resting against the stay-plate thereof, substantially as described. 70

3. The combination, with the revolving chair-spindle, and with the base-socket to receive and support the same, of the stop or lug interposed between said spindle and socket to arrest the rotation of the spindle, substantially as described. 85

JOSEPH W. KENNA.
